COUNTER MECHANISM FOR CAN COVERS

Felix Huntar, Livingston, N. J., assignor to American Can Company, New York, N. Y., a corporation of New Jersey

Application September 25, 1946, Serial No. 699,128

4 Claims. (Cl. 235—98)

1

The present invention relates to a continuous operation counter mechanism for can making machinery and has particular reference to devices for interrupting the operation of such a mechanism when an article is missed and is not to be counted.

An object of the invention is the provision of a counter mechanism wherein continuous counting of articles fed in consecutive order may be obtained so as to minimize wear and tear on the mechanism through rapid starting and stopping or otherwise tripping the mechanism.

Another object is the provision of such a counter mechanism wherein the continuous operation of the mechanism may be rapidly and accurately interrupted to prevent the counting of any articles which may be skipped or missed.

Another object is the provision of such a counter mechanism wherein interruption of the continuous operation of the mechanism is effected in time with the feeding of the articles so as to insure accuracy of the count.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a feeding device and a counter mechanism embodying the instant invention, with parts broken away;

Fig. 2 is a side view of the mechanism shown in Fig. 1, with parts broken back and shown in section;

Fig. 3 is an elevational detail of the mechanism; and

Fig. 4 is a plan view in diagram of one form of machine in which the counter mechanism of the present invention can be used.

As a preferred embodiment of the instant invention the drawings illustrate a counter mechanism for counting can covers or end members A (Figs. 1 and 2) as they are fed from a cover feeding device which may be a portion of a more elaborate can making machine.

The covers A are fed from the bottom of a supply stack of such covers retained in a magazine 11. The magazine is provided with a slightly inclined stack support 12 secured to a frame 13 which may be the main frame of the can mak-

2

ing machine to which the cover feeding device is attached.

The lowermost cover A in the supply stack is disposed over an opening 15 in the frame 13. The edge of this lowermost cover, adjacent the stack support 12, rests on a ledge 16 formed on the stack support. Opposite the stack support, the edge of the cover is supported on a peripheral bead 18 of an annular continuously rotating separator disk 19. This disk is secured to the upper face of a separator screw 21 having a spiral groove 22 cut into its outer surface. The upper or entrance end of the groove is adjacent the separator disk 19 and it communicates with a separator notch 23 formed in the bead 18 and in the peripheral edge of the disk.

The separator disk 19 and its separator screw 21 constitute a separator element for separating the lowermost cover A from the stack. This element is mounted on a continuously rotating vertical separator drive shaft 26 which is supported in suitable bearings formed in the frame 13. The shaft is rotated in any suitable manner in time with other moving parts of the machine. This is a conventional cover separator device.

In such a device, rotation of the separator element brings the separator notch 23 adjacent the inner supported edge of the cover A and thus permits the cover to enter the spiral groove 22.

With continued rotation of the separator element, the edge of the cover rides down along the spiral groove and this separates the cover from the remaining covers in the stack. This separating action also pivots the cover on the support ledge 16 into a downwardly and oppositely inclined position.

In this inclined position the separated cover A is in the path of travel of a feed finger 27 which is mounted on and which rotates with the drive shaft 26. The rotating finger 27 engages behind the separated cover and propels it along a curved path of travel to any suitable place of deposit, such, for example, as onto a waiting can for attachment thereto.

Provision is made for nullifying the action of the cover separator element to prevent the feeding of a cover from the supply stack under certain conditions, as for example, when there is no can in place to receive a cover. Withholding of a cover from separation from the supply stack

is brought about preferably by a normally stationary, annular slide or cut-out member 31 which rests on top of the separator disk 19 within its cover support bead 18.

Adjacent the cover magazine 11, the cut-out member 31 is formed with a cut-out ledge 32 which is insertable under the edge of the lowermost cover in the supply stack when the cut-out member moves toward the stack. The cut-out member 31 surrounds the separator drive shaft 26 and for this purpose it is provided with a clearance opening 33. This clearance opening permits sliding of the cut-out member across the top of the separator disk 19.

Shifting of the cut-out member 31 is effected through an arm 36 which extends out from the member on its side opposite the ledge 32. The outer end of the arm is connected to a shift lever or element 38 which is carried on a pivot pin 39 secured in a portion of the frame 13. The shift lever may be rocked on its pivot pin in any suitable manner. One embodiment in which this device has been successfully used is by selective engagement with one or the other of a pair of projections 40 which extend out from the lever and which are utilized by a trip mechanism operated by cans passing through the machine for the reception of the covers being counted. This trip mechanism is illustrated and described in detail in my co-pending application Serial No. 699,129 filed coincidentally with this present application and issued October 18, 1949 as Patent Number 2,484,830.

When the shift lever 38 is rocked to slide the cut-out member 31 into non-feeding position, the ledge 32 moves into a position adjacent the separator disk bead 18 where it engages under the edge of the lowermost cover A being supported by the bead. Hence when the separator notch 23 comes adjacent the stack of covers, the cut-out ledge 32 holds the lowermost cover in position in the stack and thereby prevents it from falling into the notch. Thus the cover is prevented from being separated from the stack and this prevents feeding of a cover.

As long as the cut-out member 31 is held in a retracted or feeding position, the covers A are separated from the stack consecutively and are fed forward in the same order. As they are separated and fed forward they are counted by a continuously operating counting mechanism which includes a commercial counter 41 carried on a bracket 42 bolted to an upright portion of the frame 13.

The counter 41 is driven by a counter shaft 43 having a worm wheel 44 mounted on its outer end. The worm wheel meshes with a worm 45 which is loosely carried on the upper end of the separator drive shaft 26. The worm normally rotates with the shaft through a friction or slip clutch connection therewith. For this latter purpose the lower end of the worm is provided with a pair of depending clutch dogs 47 which normally engage against a similar pair of upwardly projecting clutch dogs 48 formed on a clutch collar 49 slideably mounted on the separator drive shaft 26. The collar rotates with the shaft through a pin 50 which is secured in the shaft. The ends of the pin operate in slots 51 formed in the collar (see Fig. 3). The clutch collar is held in operative position against the pin 50 by a compression spring 52 which is interposed between the collar and a barrel cam 53 which is secured to the separator drive shaft 26 just above the top of the cut-out member 31.

Thus as long as covers A continue to be separated from their supply stack, the separator drive shaft 26, through its slip clutch dogs 47, 48 continuously rotates the worm 45 and worm wheel 44 and thus keeps the counter 41 operating continuously. For every cover A fed from its magazine 11, the separator drive shaft 26 and hence the worm 45 makes one complete revolution. However, in order to reduce wear on the mechanism to a minimum, the counter 41 is provided with an internal speed reducer device, to count the fed covers only in groups of ten. Hence for every ten revolutions of the worm 45, the counter through its meshing worm wheel 44 will count one group of the covers.

When a cover A is prevented from being separated from its stack and thus prevented from being fed forward, by movement of the cut-out member 31 into non-feeding position as hereinbefore explained, the rotation of the worm 45 is temporarily stopped and thus the operation of the counter is interrupted to prevent the counting of the skipped or missing cover or covers. This interruption in the count is effected by a stop bar 55 which is disposed adjacent the worm 45.

The stop bar 55 operates in a slideway formed in a stationary lug 56 carried on the bracket 42. One end of this bar is pivotally connected to the upper end of the shift lever 38. The opposite end of the bar is formed with a right angle hook section 57 which extends adjacent the path of travel of a stop lug 58 formed on the rotating worm 45 adjacent its lower end.

Under normal operation, when the cut-out member 31 is in cover feeding position (in Figs. 1 and 2) the stop lug 58 as it rotates with the worm 45 clears the hook end 57 of the stop bar 55. This permits continuous counting of the fed covers A. When a cover is missed, as by the shifting of the lever 38 and the attached cut-out member 31 the lever also slides the stop bar 55 toward the right as viewed in Figs. 1 and 2 and thus interposes its hook end 57 into the path of travel of the stop lug 58 on the worm 45. Hence the lug engages against the stop bar and thus the worm is stopped from rotating. Stopping of the worm puts a strain on the slip clutch and causes the clutch dogs 48 to ride over the stopped clutch dogs 47 against the resistance of the spring 52. This slip clutch action permits the worm to remain stopped while the separator drive shaft 26 continues to rotate.

The worm 45 is held stopped for one complete revolution of the separator drive shaft 26 and thus counting of the missed cover is prevented.

As soon as the shift lever 38 again moves the cut-out member 31 into feeding position to again permit feeding of the covers, the stop bar is removed from the path of travel of the stop lug 58 on the worm. The meshing worm wheel locks the worm against rotation with the separator drive shaft 26 until the clutch dogs 48 again become engaged with the clutch dogs 47. In this manner the rotation of the worm is kept in synchronism with the rotation of the separator drive shaft.

Mention has already been made of the trip mechanism operated by a can. Such a trip mechanism places the shift lever 38 and with it the cut-out member 31 in cover feeding position when a can passes the actuating part of the trip mechanism. Fig. 4 diagrammatically shows a runway for cans AA and such cans are retained in a straight line by spaced, parallel guide rails 100. In one section of this runway on one side

there is disposed a feeler 114 constituting a can actuated part of the trip mechanism. Feeler 114 when engaged by the can moves the shift lever 38 into the position shown in Fig. 2. This is the cover feeding position of the cut-out member 31 already described.

The connection between the feeler 114 and the shift lever 38 is made through link and bell crank elements connecting with a rod 119. The rod 119 at the opposite end connects with a forked rocker head 120 (see also Fig. 2) which carries a pair of loose fingers 121. The rocker head is mounted on a pivot shaft 122 (Fig. 4) which is carried in the frame of the machine. This connection between rocker head 120 and feeler 114 is for the purpose of moving the rocker head to position one of the pair of loose fingers 121 so as to make such a finger effective against one of the projections 40 on the shift lever 38. This makes it possible to move the latter in the desired direction.

Movement of the shift lever is made through the positive action of a continuously moving hammer 123 actuated by the cam 53. Hammer 123 is pivotally mounted at 124 on the frame of the machine and is formed with an arm 125 which carries a cam roller 126. This roller operates in a peripheral groove 127 of the barrel cam 53. Rotation of the drive shaft 26 with the cam 53 causes pivoting of the hammer on its pivotal axis. Thus the hammer 123 swings toward the shift lever 38 for each rotation of the feed finger 27.

The hammer 123 is formed with an upper projection 128 and a lower projection 129 both on the right or forward surface of the hammer, as viewed in Fig. 2. When a can AA engages the feeler 114 (Fig. 4) the rocker head 120 lifts both fingers 121 into a raised position, this being the position shown in Fig. 2.

This positioning of the parts brings the upper finger above the hammer 123 and places the lower finger in between the lower projection 129 of the hammer and the lower projection 40 of the shift lever 38. When the hammer 123 moves on the following reciprocating stroke (toward the right as viewed in Fig. 2) it strikes against the lower interposed finger 121 swinging it in a clockwise direction. This moving finger striking against the lower projection 40 of the shift lever 38 causes the lever to move in a counter-clockwise direction. This action withdraws the cut-out ledge 32 of the cut-out member 31 from its withholding position and the cover A is separated from the magazine 11 and is counted, as already fully described.

A spring 131 (Fig. 4) connecting with one end of the rod 119 and secured to a stationary part of the frame swings the feeler 114 of the trip mechanism back into the can runway when an advancing can passes and releases the feeler. This moves the connecting parts into different positions, thus lowering the rocker head 120. When the rocker head 120 is in lowered position the lower finger 129 of the head is below the hammer projection 129 and below the lower projection 40 of the shift lever 38.

Upon the succeeding stroke of the hammer 123, its upper projection 128 strikes the upper rocker head finger 121 moving it against the upper projection 40 of the shift lever 38 thereby swinging the lever in a clockwise direction and inserting the cut-out ledge 32 of the cut-out member 31 into cover withholding position. Therefore no

cover will be fed on the next cycle and no count will be registered on the counter 41.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a counter mechanism, the combination of continuously operating separator means for engaging and separating articles, a drive shaft for actuating said separator means, withholding means having movement into article withholding position for nullifying the article separating action of said separator means, shifting means connected with said withholding means for moving it into its withholding position, a counter disposed adjacent said separator means, counter driving means interposed between said drive shaft and said counter for operating the counter, and means connected with said shifting means for preventing operation of said counter driving means when said withholding means is in said withholding position to stop the count.

2. In a counter mechanism, the combination of continuously rotating separator means for engaging and separating can covers from a stack of covers, a drive shaft for rotating said separator means, withholding means having movement into cover withholding position for nullifying the separating action of said separator means, shifting means connected with said withholding means for moving it toward said stack of covers into its withholding position, a counter disposed adjacent said separator means, counter driving means interposed between said drive shaft and said counter for operating the counter, and means connected with said shifting means for preventing operation of said counter driving means and the counter operated thereby when said withholding means is moved into its withholding position by said shifting means.

3. In a counter mechanism, the combination of continuously operating separator means for engaging and separating articles, a drive shaft for said separator means, withholding means adjacent said separator means and having movement into article withholding position for preventing separation of the articles, means for moving said withholding means, a counter disposed adjacent said separator means for counting the operative cycles of said separator means, counter driving means having a part loosely mounted on said drive shaft, a slip clutch disposed between said counter driving means and said drive shaft for normally actuating said counter driving means, and stop means movable by said withholding moving means for disconnecting said counter driving means from said drive shaft by breaking the operating connection in said slip clutch.

4. In a counter mechanism, the combination of continuously rotating separator means for engaging and separating can covers from a stack of covers, a drive shaft for said separator means, withholding means slidably mounted above said separator means and having a cut-out ledge movable under the lowermost cover in the stack to nullify the operation of said separator means, actuating means for sliding said withholding means into cover withholding position, a counter

disposed adjacent said separator means for counting the operative cycles of said separator means, a worm loosely mounted on said drive shaft, a slip clutch disposed between said worm and said drive shaft for normally rotating the worm, a stop lug on said worm, and a stop bar connected with said actuating means and movable thereby into the path of said worm stop lug for actuating said slip clutch to stop counting of said counter when said cut-out ledge is under said lowermost cover.

FELIX HUNTER.
